US00D457330S

(12) **United States Design Patent** (10) Patent No.: **US D457,330 S**
Woodbridge et al. (45) Date of Patent: ** May 21, 2002

(54) **SHEET MATERIAL**

(75) Inventors: **Timothy John Woodbridge, Hertfordshire; Leslie James Squires, Lancashire, both of (GB)**

(73) Assignee: **Hunt Technology Limited, London (GB)**

(**) Term: **14 Years**

(21) Appl. No.: **29/123,362**

(22) Filed: **May 16, 2000**

(30) **Foreign Application Priority Data**

Nov. 16, 1999 (GB) 2088122

(51) LOC (7) Cl. **05-06**

(52) U.S. Cl. **D5/47**

(58) **Field of Search** ..... D5/1, 2, 6, 11, D5/16, 19, 20, 24, 25, 26, 27, 28, 32, 35, 37, 38, 39, 45, 47, 49, 50, 52, 53, 54, 55, 56, 57, 58, 59, 60, 61, 62, 63, 66, 99; D2/635, 638, 749, 883, 889, 980, 984, 994; D6/613, 595, 603, 608, 596, 604, 606, 615, 616, 617; D24/124, 125; D25/142, 157, 163; 428/154, 156, 171, 187, 199, 542.6, 904.4, 542.2, 198, 17, 35.6, 36.1; 5/413 AM, 709; D7/396.4, 396.5; D9/310; 162/134, 231, 140; 156/209; 442/171, 398, 35, 57, 60
